UNITED STATES PATENT OFFICE.

GEORGE W. FURTH, OF CLEVELAND, OHIO.

BALING-TIE BUCKLE.

1,084,002.

Specification of Letters Patent.

Patented Jan. 13, 1914.

Application filed June 12, 1912. Serial No. 703,308.

To all whom it may concern:

Be it known that I, GEORGE W. FURTH, a citizen of the United States, residing at Cleveland, in the county of Cuyahoga and 5 State of Ohio, have invented a new and useful Baling-Tie Buckle, of which the following is a specification.

One object of the present invention is to provide a device of the character above mentioned, having novel means for holding and receiving the ends of the binder, novel means being provided for retaining the ends 10 of the binder against displacement.

A further object of the invention is to 15 provide a device of this type with which the binder may be assembled readily, there being a straight pull upon the device, due to the action of the binder.

With the foregoing and other objects in 20 view, which will appear as the description proceeds, the invention resides in the combination and arrangement of parts and in the details of construction hereinafter described and claimed, it being understood 25 that changes in the precise embodiment of invention herein disclosed can be made within the scope of what is claimed without departing from the spirit of the invention.

In the drawings,—Figure 1 shows the invention in perspective, assembled with the binder and with the contained material; Fig. 2 shows the invention in perspective; Fig. 3 is a top plan, showing the ends of 30 the binder assembled with the buckle; Fig. 35 4 is a view similar to Fig. 3 but showing the wing bent down to retain one end of the binder; Fig. 5 is a section on the line 5—5 of Fig. 3; and Fig. 6 is a side elevation showing a modified form of the invention.

40 The device herein disclosed is fashioned from a flat plate of metal and comprises a body, the same including a shank 1 provided at one end with a laterally enlarged head 2, one edge of which slants toward the shank 45 1 as indicated at 3. Upstanding from one edge of the shank 1 is a wing 4, the end edges of which converge as indicated at 5 toward the body 1, there being enlarged seats 6 formed at the point of juncture between the 50 wing 5 and the shank 1. Depending from that edge of the shank 1 which carries the wing 4, and located adjacent the free end of said edge is a depending prong 7. The 55 prong 7 is a useful but not absolutely necessary portion of the structure.

Depending from the free end of the head

2 is a flange 8. The flange 8 is disposed approximately at right angles to the head 2 and extends transversely of the wing 4. In the flange 8 there is an opening 9. It has 60 been pointed out hereinbefore that the wing 4 upstands from one edge of the shank 1. In the opposite edge of the shank 1 there is a diagonal slot 10, extended into the head 2 and terminated at its inner end in an enlarged seat 11 located adjacent the flange 8. The slot 10 serves to define a prong 12 in the head 2.

In operation, the body portion of the device is placed upon the upper face of the 70 material 14, the flange 8 extending along one side face of the material. When the prong 7 is employed, the same is seated into the material 14 by a hammer blow. The binder is denoted by the numeral 15, and 75 a hook 16 is formed in the binder by passing the free end 17 of the binder through the opening 9, from the inside. The containing end of the binder is then passed through the slot 10 from below. When the 80 continuing end of the binder rests in the seat 11, the binder is bent over the flange 8, thus forming a secure, hooked connection. The binder is passed around the material and is wrapped around the wing 4. The 85 wing 4 is then beaten down into approximate parallelism with the shank 1, as shown in Fig. 4, so as to hold the wing-engaged end of the binder against displacement.

It is to be noted that the seat 11, the wing 90 4, and the prong 7, when the latter is used, are all located in alinement. Consequently, the binder 15 will exert a straight pull to the buckle. When the hook 16 of the binder 95 15 is placed about the prong 12, the slot 10 95 serves to guide the hook 16 into the seat 11, and when the hook 16 is engaged in the seat 11, the bill 17 of the hook will be alined with the opening 9, so that by exerting a pull upon the binder, the bill 17 100 of the hook will emerge from the opening 9. The converging edges 5 of the wing 4, together with the enlarged seats 6 serve to retain the binder against displacement, and when the wing 4 is beaten down into parallelism with the shank 1, as shown in Fig. 4, the displacement of the wing-engaging 105 end of the binder will be a practical impossibility.

As indicated in Fig. 6, both corners of the 110 part 1 may be equipped with prongs, the additional prong being designated in Fig.

6 by the reference character 7^a. Furthermore, the part 12 may be bent rectangularly, in its intermediate portion, to form a prong 12^a.

5 Having thus described the invention, what is claimed is:—

1. A bale tie buckle comprising a body provided at one end with a depending flange having an opening, the body being provided
- 10 along one edge with a bendable wing, there being a diagonal slot in the other edge of the body defining a pointed tongue in the body, the tongue being independent of the flange; the inner end of the slot being
- 15 spaced from the flange and being disposed adjacent the opening.

2. A bale tie buckle comprising a body provided at one end with a depending flange, there being an opening in the flange and an opening in the body, the body being provided along one side edge with a bendable wing, the prolonged line of juncture between the wing and the body lying in a common plane with both openings.

In testimony that I claim the foregoing 25 as my own, I have hereto affixed my signature in the presence of two witnesses.

GEORGE W. FURTH.
